UNITED STATES PATENT OFFICE.

EDUARD LEISSNER, OF NEW YORK, N. Y.

DESIGN FOR WALL-PAPER.

SPECIFICATION forming part of Design No. 12,009, dated November 2, 1880.

Application filed August 19, 1880. Term of patent 3½ years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics; and it consists in the novel grouping and configuration of figures hereinafter more fully described.

The accompanying photograph illustrates a face view of wall-paper having my new design.

The background of the paper consists of a series of lozenge-shaped figures, A, placed in varying directions. Each of these figures A is ornamented with a zigzag pattern running from end to end. On this background so ornamented are placed the several figures and groups hereinafter described.

10 a is a group consisting of two flower-like figures, one overlapping the other. b is a group which appears in the corner of the design, but half the group being shown in each corner. It consists in a circle containing leaves and partly overlapping a rosette.

15 d is a group consisting of a circular figure with dotted lines radiating from its center, partly overlapped by a flower-shaped figure resembling a daisy. f is a group composed of

20 two circular figures, the one ornamented with dots and arcs of flower-shaped figures and overlapped by the other, which has an ornamentation of oblong leaves. g is a circular figure with a star-like center surrounded by

25 radiating leaves. h is a rosette with widely-open leaves and dotted center. i is a figure consisting of a circle containing pointed leaves with dots between them, said leaves starting from the periphery of the figure. j is a figure resembling an open rose. k is a figure consisting of a circle containing a branch with a flower and twigs thereon. l is a group consisting of two flower-like circular figures, one overlapping the other.

All the above-mentioned figures are arranged upon the patterned background.

I claim—
